UNITED STATES PATENT OFFICE.

FREDERIC D. BLAUVELT, OF GLEN RIDGE, NEW JERSEY.

WATER-SUPPLY FIXTURE.

Application filed November 24, 1924. Serial No. 751,746.

This invention relates to water supply fixtures for hot and cold water, and the object of the invention is to provide an improved fixture especially intended for wash basins, or lavatories, and bath tubs. More particularly, the invention aims to provide a fixture for supplying hot and cold water, and desirably also for controlling the basin or tub stopper, in which the flow passage for the hot and cold water and the operating connections for the separate hot and cold water valves and the stopper are contained within a single body or casing adapted to be set in an opening in the wall or slab of the basin or tub and having operating handles in juxtaposition at the outer end of the casing and the supply connections and flow controlling valves and connections to the stopper at the opposite end of the casing.

The fixture thus requires only one hole through the wall of the basin or tub, usually the horizontal wall at the edge of the basin or tub. The exposed parts of the fixture may be made very compact and of pleasing design, and it is especially convenient for the user. Because of the single hole required, it is convenient and relatively inexpensive to install, and the construction is such that the cost of maintenance is also relatively low.

A full understanding of the invention can best be given by a detailed description of a fixture of approved form embodying all the features of the invention, and such a description will now be given in connection with the accompanying drawings which illustrate a basin fixture made in accordance with the invention. In said drawings:

Fig. 1 is a central sectional view of the fixture;

Fig. 2 is a section taken at right angles to Fig. 1;

Fig. 3 is a view showing the fitting in side elevation, and showing also in section a part of the wall of a basin in the upper horizontal portion of which the fixture is mounted, and showing the drain connection and stopper connected to be operated by the stopper rod of the fixture;

Fig. 4 is a top plan view taken on line 4-4 of Fig. 3;

Figs. 5 and 6 are sectional plan views taken on lines 5-5 and 6-6 of Fig. 1;

Fig. 7 is a plan view of the non-rotatable washer between the handle disks;

Fig. 8 is a detail view showing the valve-55 operating cams; and

Fig. 9 is a perspective view of one of the tension springs for the operating handles.

Referring to the drawings, the fixture has a hollow body, or main casing, 10 adapted to be set and secured in an opening in the basin or tub wall 11 having at its upper or outer end a shoulder 12 to rest on the wall and being secured by a ring nut 13 screwed on to the lower threaded portion of the casing. The casing is closed at its upper end except for a central threaded opening and a discharge spout 14 which extends from one side of the upper end of the casing. The lower end of the casing is open and has secured to it an extension member 15 of hollow cylindrical form made open at both ends and having on opposite sides inlet openings 16 through short threaded bosses. The extension member is for convenience 75 in assembling secured to the casing 10 by means of a flanged collar 17 which is screwed on the upper end of the extension piece and is secured to the lower end of the casing 10 by means of a flanged ring nut 18 80 screwed on the slightly reduced end of the casing. The space within the casing and extension member 15 is partitioned to provide a water space or chamber and an open ended space extending from the upper end of 85 the fixture to the lower end of the extension member sealed from the water chamber. For this purpose in the construction shown, a tube 20, most desirably of thin copper, is provided having an inwardly turned flange 90 at its upper end which is clamped against the upper end of the casing by means of a flanged bushing 21 which is screwed upward into the threaded opening in the end of the casing, and having at its lower end an outwardly turned flange which is clamped against the lower end of the extension member 15 by means of a cap piece 22 which is screwed on the lower end of the member 15. The tube 20 thus forms a watertight partition between the central space within the tube and the surrounding water-space or chamber 23 into which the water passes 100 from the inlet openings 16 and from which it flows through the spout 14.

Two valves 25 and 26 for controlling the supply of hot and cold water respectively are attached to the extension member 15.

Each of these valves comprises a body casing 27 which is most desirably of cylindrical form and made open at both ends, and each has an inlet through an extension 28 from 5 one side at its outer end for connection to a supply pipe and an outlet through an extension 29 to which is screw connected a short flanged connecting pipe 30 which is secured by a ring nut 31 to the threaded 10 boss about one of the inlet openings 16 of the part 15. Through these connections the valves are supported from the extension member 15. They are set in alignment with each other with their common axis intersecting 15 at right angles the axis of the main casing 10 and tube 20. The inner ends of the valve casings are spaced apart and connected by a sleeve 32. The outer ends of the valve casings are closed by caps 33 and the 20 chamber within the casing of each valve is divided between the inlet and outlet by a partition disk 34 which has a central port 35.

The flow of water through the port 35 is controlled by a valve head 36 which closes 25 in the direction of water flow and seats against a seat formed about the edge of the opening 35. The valve head is pressed toward its seat by a spring 37 and is carried by a stem 38 which extends through a central opening in a disk 40 screwed into the rear end of the valve casing. The passage 30 of water out through the rear end of the valve casing is prevented by a corrugated cylindrical diaphragm, or bellows, 41, of flexible metal which has at one end an inward flange which is clamped between a disk flange 42 on the valve rod and a flange 35 on the end of a sleeve 44 which carries the valve head and is screwed on to the threaded reduced end of the valve rod. The other 40 end of the bellows has an outward flange which is clamped against the plate 40 by a ring nut 45.

The valves are operated by means of handles 50 and 51 through concentric tubular spindles 52 and 53 which extend through the tube 20 and cams 54 and 55 on the lower ends of the spindles. The spindles 52 and 53 extend down through an upper opening 50 56 in the sleeve 32. The bushing 21 serves as a bearing for the upper end of the outer spindle 52, and the cap 22 provides a bearing for the lower end of this spindle, and the spindle 52 provides a bearing for the inner spindle 53. The reason for making the inner spindle tubular is to accommodate a stopper-operating rod as hereinafter explained. The handles 50 and 51 when in normal closed, or "off" position extend outward, desirably in opposite directions and in the same horizontal plane, from disks 60 and 61. The disk 60 is mounted on the upper end of the spindle 52 and secured by a set screw 62 (Fig. 6). The spindle 52 65 does not extend upward above the disk 60,

and the disk 61 is mounted on the upwardly extending end of the spindle 53 and secured by a set screw 63.

The handle disk 60 seats on a disk 64 which is screwed on the bushing 21 down 70 against the top of the casing 10. Above the disk 64 the bushing is cut away except for two segmental portions 65 which extend up through the handle disks. The handle disks are formed with segmental cut outs to receive the upward extensions of the bushing, the cut outs 66 of the disk 60 being so located and of such length as to permit the handle to be turned forward from its normal position the desired amount, that is, in the 75 fixture shown, through about 45°, and the cut outs 67 of the disk 61 being so located and of such length that the handle 51 may be turned forward a similar distance from its normal position. A disk 70 rests on the 80 top of the upper handle disk 61, and a cap nut 71 screwed on to the ends of the upward extensions 65 of the bushing 21 holds the disk 70 in place. To prevent the turning movement of one handle disk causing a 85 turning of the other handle disk, a non-turnable washer 72 is provided between the two handle disks, this washer being held against turning by having its central opening formed with inward projections to extend between the segmental extension 65 of the bushing 21 as shown by Fig. 7.

In order to avoid lost motion between the handle disks and the disks 64 and 70, and on the other hand, to avoid having the handle 90 disks held too tightly between the disks 64 and 70, while securing a desirable snug fit and easy resistance to movement of the handles, spring rings 73 are provided, one set in a channel in the upper face of the disk 105 64 to bear against the under face of the handle disk 61, and the other set in a channel in the under face of the disk 70 to bear against the upper face of the handle disk 61. These spring rings may be of spring 110 wire of a diameter less than the depth of the channels and bent in an axial direction to bear against the bottom of the channel and the face of the handle disk at spaced points. 115

The cam 54 is made hollow on its under side to accommodate the cam 55 as shown in Fig. 1. When the operating handles 50 and 51 are in their normal or "off" position, low points of the cams 54 and 55 120 are opposite the respective valve rods 38, and the cams are shaped so that when either operating handle is moved forward the corresponding cam will push its co-operating valve rod outward to force the 125 valve head 36 away from its seat against the pressure of its spring 37. When the operating handle is moved back to normal position the cam permits the valve head to be closed against its seat under the action of its 130

spring. The inclination of the operating faces of the cams is desirably such that the pressure of the valve stem when the valve has been opened more or less will not turn the 5 cam and its spindle and operating handle back to "off" position. The fixture thus has non-selfclosing valves. Such a non-selfclosing fixture is usually most desirable, but the construction shown is not to be 10 considered as limited to this non-selfclosing feature, as, if the cam inclinations were made suitably abrupt, then the spring-pressed valve stems acting on the cams would turn the spindle and handles back to normal 15 position when released after being turned to open, or "on", position.

As is usually desirable, and as shown, the fixture is provided with stopper-operating means. For this purpose, the spindle 53 is 20 made tubular and a stopper-operating rod 80 is provided which extends through the spindle 53 and finds its bearing therein. The upper end of the rod 80 extends through an opening in the cap nut 71 and has fastened to it an operating knob 81. The lower end of the rod projects through an opening in the lower side of the sleeve 32 and is adapted to operate a stopper through suitable connections. In the example shown, 25 the end of the rod is threaded and has screwed thereon a connecting yoke 82 which is pivotally connected to a link 83 the lower end of which is pivoted to a short arm 84 on a rock rod 85 extending from a basin 30 outlet fitting 86 which may be of any suitable construction such that the turning of the rod 85 raises or lowers the basin stopper 87. The threaded connection between the 35 yoke 82 and the lower end of the operating rod 80 provides for an adjustment longitudinally of the rod, and a lock nut is provided for setting the ports when adjusted. The arm 84 is longitudinally adjustable on the rod 85. Provision is thus made for adjustment 40 of the stopper-operating connections in two directions at right angles to each other.

It will be seen that the construction of the fixture is such that it may be readily installed in position or removed or taken apart for access to its different parts. For installation it is necessary only that the valves 25 and 26 be disconnected from the assembled main portion of the fixture by unscrewing the ring nuts 31. The assembled main casing 10 and extension member 15 with the other parts carried thereby, and the ring nut 13 being removed, then have no parts projecting beyond the dimensions of the main body portion of the main casing below its upper shoulder 12, so that this part of the fixture may be placed in position in the opening in the basin or tube wall from above. The ring nut 13 is then screwed up

on the threaded portion of the casing against 65 the bottom wall. The valves, connected by the sleeve 32, are then positioned with relation to the extension member 15 and secured by the flanged ring nuts 31, and connection is made between the lower end of the stopper rod 80 and the stopper-operating mechanism and the hot water supply pipes are connected to the valve casings. If access to either of the valves becomes necessary, the valves are readily removable by simply unscrewing the ring nuts 31 and dropping the valves away from the body portion of the fitting, and disconnecting the yoke 82 from the rod 80. The sleeve 32 by which the inner ends of the valve casings are connected desirably has a threaded connection with one of the valve casings and a slip-on connection with the other, or the arrangement may be otherwise such that the valves when removed from the body of the fitting may be readily 85 separated. The sleeve 32 is desirably of such length as to extend the valve casings a sufficient distance to hold the casings substantially rigidly together and prevent relative movement of the casings, thus preventing any turning strain on the connections between the valve casings and the extension member 15. If desired, either valve may be removed without disconnecting the other valve from the member 15. The interior of 90 either valve is also readily accessible without moving the valves from the main body of the fixture by simply unscrewing the cap 33, and if it is desired to go further, unscrewing the sleeve 44 and the partition 100 disk 34.

The use in the claims of the terms "upper" and "lower" and other terms referring to the fixture or parts thereof as though the fixture were set, as it usually is, with its principal axis vertical, is for convenience and is not to be taken as limiting the invention to a fixture set vertically.

What is claimed is:

1. A water supply fixture, comprising in combination a main casing adapted to be set in a supporting wall and having a spout at its upper end and two lateral inlet openings at its lower end, two valve casings positioned adjacent the lower end of the main casing each having an inlet opening for connection with a supply pipe and an upward extension having an outlet passage, means for detachably connecting said upward extensions to the main casing and joining said outlet passages to the inlet openings of the main casing, a sleeve extending between the ends of the valve casings below the lower end of the main casing and holding the valve casings rigidly in axial alignment when they are connected to the main casing, a valve mounted within each valve casing, valve operating means at the upper end of the

main casing, and connections extending from said operating means through the main casing to the space within said sleeve between the adjoining ends of the valve casings for 5 operating said valves.

2. A water supply fixture, comprising in combination a main casing adapted to be set in a supporting wall and having a spout at its upper end and two lateral inlet openings at its lower end, two concentric valve operating spindles extending through the main casing, means at the upper end of the main casing for turning said spindles, two valve casings positioned adjacent the lower 10 end of the main casing each having an inlet opening for connection with a supply pipe and an upward extension having an outlet passage, means for detachably connecting said upward extensions to the main casing 15 and joining said outlet passages to the inlet openings of the main casing, the valve casings being positioned in axial alignment and rigidly connected together by a sleeve extending between the ends of the valve casings below the lower end of the main casing, a valve mounted in each valve casing having a stem extending toward the axis of said operating spindles, and a cam on each of said spindles within said sleeve for 20 coaxing with one of said valve stems.

3. A water supply fixture, comprising in combination a main casing adapted to be set in an opening in a supporting wall and having a spout extending from its upper end and 25 having a threaded opening in its upper end wall, a tube within the casing extending from the upper to the lower end thereof having an inward flange at its upper end clamped against the upper end wall of the casing by a flanged bushing screwed into the opening in said wall and having an outward flange at its lower end clamped against a part of the casing, thereby providing a water chamber within the casing extending 30 from the lower to the upper end thereof sealed from the space within the tube, means providing a valve-controlled inlet passage leading to the water chamber at the lower end of the casing, a tubular valve-operating 35 spindle extending through said tube and having a bearing in said bushing, a handle member on the upper end of said spindle, said bushing having segmental extensions projecting upward through cut-outs in the handle member, the relative circumferential length of said extensions and of said cut-outs being such as to permit a limited turning movement of the handle member and spindle, and a top piece screwed on said extensions of said bushing.

4. A water supply fixture, comprising in combination a main casing adapted to be set in an opening in a supporting wall and having a spout extending from its upper end 40 and having a threaded opening in its upper

end wall, a tube within the casing extending from the upper to the lower end thereof having an inward flange at its upper end clamped against the upper end wall of the casing by a flanged bushing screwed into the opening in said wall and having an outward flange at its lower end clamped against a part of the casing, thereby providing a water chamber within the casing extending from the lower to the upper end thereof sealed from the space within the tube, valve-controlled inlet passages leading to the water chamber at the lower end of the casing, a tubular valve-operating spindle extending through said tube and having a bearing in 50 said bushing, a valve-operating spindle within said tubular spindle, two handle disks mounted above said casing one over the other, the lower one being fastened to the upper end of said tubular spindle and the upper one being fastened to the upper end of the second said spindle, said bushing having segmental extensions projecting upward through cut-outs in the two handle disks, the relative circumferential length of said extensions and of said cut-outs of each handle disk being such as to permit a limited turning movement of each handle disk and the spindle to which it is fastened, a top piece screwed on said extensions of said bushing, means bearing against the under face of the lower handle disk and the upper face of the upper handle disk including means for applying yielding pressure to the disks, and a non-rotatable 55 washer between the disks.

5. A water supply fixture, comprising in combination a main casing adapted to be set in an opening in a supporting wall, said casing comprising an upper body member and an extension member detachably connected to the body member by a flanged collar screwed on one of said members and a flanged ring nut screwed on the other of said members, the body member having a spout at its upper end to extend above the supporting wall and having a threaded opening in its upper end wall and the extension member having two lateral inlet openings, a partition tube within the casing extending from the upper end of the body member to the lower end of the extension member and having an inward flange at its upper end clamped against the end wall of the body member by a flanged bushing screwed in the opening in said end wall and having an outward flange at its lower end clamped against the extension member by a cap screwed on the lower end of said member, thereby providing a water chamber within the main casing extending upward from said inlet openings sealed from the space within the tube, means providing valve-controlled inlet passages leading to said inlet openings, a tubular valve- 130

operating spindle extending through said tube and through said bushing and through an opening in the screw cap at the lower end of the casing, said bushing and said screw cap providing bearings for said spindle, a tubular valve-operating spindle mounted within the first said spindle and extending beyond the upper and lower ends of the first said spindle, and operating handles connected one to the upper end of each of said spindles for turning the spindle.

6. A water supply fixture, comprising in combination a main casing adapted to be set in an opening in a supporting wall and having an opening at its upper end, the casing being interiorly partitioned to provide a space for operating connections extending downward from said end opening and a water chamber within the casing extending from the lower to the upper end thereof sealed from said space, an outlet from the water chamber at the upper end of the casing, means providing a valve-controlled inlet passage leading to the water chamber at the lower end of the casing, a tubular valve-operating spindle extending through said space and through said end opening, a handle member on the upper end of said spindle, segmental extensions projecting upward through cut-outs in the handle member, the relative circumferential length of said extensions and of said cut-outs being such as to permit a limited turning movement of the handle and said spindle, a top piece secured on such extensions, and a stopper operating rod extending through said spindle

and through an opening in said top piece and having a handle on its upper end.

7. A water supply fixture, comprising in combination a casing adapted to be set in an opening in a supporting wall and having an opening at each end, a tube within the casing extending between the ends thereof and providing a passage extending between said end openings and a water chamber within the casing extending from the lower to the upper end thereof sealed from the space within the tube, an outlet from the water chamber at the upper end of the casing, valve-controlled inlet passages leading to the water chamber at the lower end of the casing, a tubular valve-operating spindle extending through said tube, a valve-operating spindle within said tubular spindle, two handle disks mounted above said casing one over the other, the lower one being mounted on the upper end of said tubular spindle and the upper one being mounted on the upper end of the second said spindle, segmental extensions projecting upward from the casing through cut-outs in the two handle disks, the relative circumferential length of said extensions and of said cut-outs of each handle disk being such as to permit a limited turning movement of each handle disk and the spindle on which it is mounted, a top piece screwed on said extensions, and a non-rotatable washer between the disks.

In testimony whereof I have hereunto set my hand.

FREDERIC D. BLAUVELT.
